(57) **CLAIM**

The ornamental design for a shoe sole, as shown and described.

DESCRIPTION

FIG. 1 is a perspective top front view of a shoe sole, showing our new design according to a first embodiment.

FIG. 2 is a perspective top rear view thereof.

FIG. 3 is a perspective bottom front view thereof.

FIG. 4 is a left view thereof.

FIG. 5 is a right view thereof.

FIG. 6 is a front view thereof.

FIG. 7 is a rear view thereof.

FIG. 8 is a top view thereof.

FIG. 9 is a bottom view thereof.

FIG. 10 is a perspective top front view of a shoe sole, showing our new design according to a second embodiment.

FIG. 11 is a perspective top rear view thereof.

FIG. 12 is a perspective bottom front view thereof.

FIG. 13 is a left view thereof.

FIG. 14 is a right view thereof.

FIG. 15 is a front view thereof.

FIG. 16 is a rear right view thereof.

FIG. 17 is a top view thereof; and,

FIG. 18 is a bottom view thereof.

The dash-dash lines represent unclaimed environmental matter and portions of the shoe sole that form no part of the claimed design. No claim is made to portions that are not shown. The claimed surfaces in FIGS. 1-to-9 are lined for contour. The claimed surfaces in FIGS. 10-to-18 are lined for translucency.

1 Claim, 16 Drawing Sheets
